CABINET

Charles L. O'Reilly, New York, N. Y.

Application October 30, 1941, Serial No. 417,096

2 Claims. (Cl. 312—185)

This invention relates to cabinets and has as its object the provision of a concealed cabinet which will be relatively simple in structure, economical in manufacture and highly efficient in use.

Another object of my invention is to provide an open face display stand upon which salable articles may be placed and which may be closed up when not in use by confining a rack with articles therein contained within a relatively small space.

Another object of this invention is the provision of a collapsible cabinet structure which provides a series of extended shelves and an illuminator all of which when not in use are adapted to be disposed in a small compact unit and locked against access.

A further object of this invention is the provision of a novel closure means for collapsible display stands together with means for locking the stand when collapsed and closed.

A still further object of my invention is the provision of a novel assembly for roll screen closure members.

Still another object of this invention is the provision in guided roll screen closure members of a guide and latch means for such closure for maintaining the latter in closed position.

Other objects and advantages reside in certain novel details of construction which will become apparent as described in the specification in view of the drawings, in which:

Fig. 1 is a perspective view of a cabinet embodying my invention;

Fig. 2 is a vertical sectional detail view of the same and at larger scale with respect to the showing in Fig. 1;

Fig. 3 is an enlarged detail section of the head structure of Fig. 2;

Fig. 4 is an enlarged detail section of the lower portion of Fig. 2 and is complementary to the head structure of Fig. 3;

Fig. 5 is a fragmentary perspective view of a guide and latch bar of the roll screen embodied in my invention;

Fig. 6 is a sectional detail of the lock and latch operating unit as seen from line 6—6 in Fig. 5;

Fig. 7 is a fragmentary perspective view of the upper end of the guide rail showing a keeper for the latch of Fig. 5;

Fig. 8 is a fragmentary perspective view of the lower end of the roll screen seen in Fig. 5;

Fig. 9 is a perspective view of a bearing used on the roller screen of Fig. 8;

Fig. 10 is an exploded perspective view of the

tensioner of the roll screen and end supports therefor;

Fig. 11 is a fragmentary perspective view of a housing for the roll screen; and

Fig. 12 is a sectional detail view of the parts seen in Figs. 8 to 11 inclusive in assembled relation.

Referring to Fig. 1 my collapsible display unit 10 is shown associated with a cabinet 11 which is adapted to be placed in public places where the goods contained in the display unit may stimulate the sale of such goods. Such a cabinet is shown and described in my copending application filed on even date herewith. The display unit is, of course, adapted to be installed in any place wherein there is provided a suitable chamber or compartment, such as the interior space 12 provided by the walls of the cabinet 11. For example, such a chamber may be provided by forming a niche in a wall of a building whereby to provide a back wall such as the wall 13 in the cabinet 11 within the recess or the space 12.

The new display unit is provided with a merchandise supporting rack 14 comprising a back panel 15 hingedly mounted at its upper end as at 16 on the inner wall 13 of the recess 12. A pair of side walls 17 extend forwardly of the back panel 15 to support a plurality of shelves 18 formed on the panel 15 on the side thereof facing an opening 19 provided by the recess 12. In the present instance each of the shelves 18 is provided with a baffle 20 in the form of a glass panel 21 having a beaded upper edge and being supported at its ends in a groove 22 formed by a portion of the side wall 17 bent inwardly toward the shelves 18 together with a pair of stamped lugs spaced therefrom a distance substantially the thickness of the glass panel 21. Thus, at each of the shelves 17 there is formed a pocket 23 wherein articles of merchandise may be lodged in full view of persons standing before the cabinet 11.

The bottommost shelf 18' of the shelves 18 has a channel-shaped finishing rail 24 suspended therefrom to shield the lower area L of the recess 12 from view. Likewise mounted on the bottom of the shelf 18' is a hinge 25 to which is attached a bracket member 26 adapted to rest upon a bar 27, later to be explained, to prop the rack 14 in an extended condition as shown in Figs. 1 and 2. Thus, the shelves are arranged in a terraced condition in a manner such that the interior of each pocket 23 may be reached from above. As seen in Figs. 2 and 4, the outward pivotal movement of the sup-

porting rack or shelf assembly 14 is limited through the medium of a chain 46', one end of which is attached as at 47' to the bracket member 26 and the opposite end attached as at 48' to the bottom wall of the cabinet.

The upper area U of the recess 12 is provided with a head plate 28 over the opening 18, which head plate 28 provides a mounting for a swinging lamp structure indicated at 29. The lamp structure 29 comprises a reflector housing 30 hingedly mounted as at 31 on the head plate 28 in such manner that the reflector 30 may be extended horizontally outside the recess 12 with the open lower side of the reflector disposed over the display rack 14. The reflector is held in extended position by means of a prop 32 hingedly mounted as at 33 just above the hinge mounting 16 of the display rack, one wall of the reflector housing 30 having an extending lug 34 against which the free end of the prop 32 is placed as shown in Fig. 2. The prop 32 in addition to supporting the reflector 30 also provides a shield and reflector surface which conceals the upper area U of the recess from view and at the same time is adapted to deflect light rays down upon the shelves 17.

Arranged in the reflector housing 30 is an illuminating means 35 in the form of an electric lamp, a fluorescent tube or the like. The arrangement is such that rays of light from the lamp 35 are deflected downwardly by the reflector 30 onto the terrace of article containing pockets 23 so that each of the pockets is illuminated and the contents thereof made more visible from the exterior of the cabinet 12.

By the foregoing arrangement I have provided a pleasing and attractive as well as an efficient and useful display stand adapted for the sale of articles such as candy, flowers, newspapers, magazines and the like, without requiring a great amount of floor space since the supporting shelves of my device are arranged in vertical alignment.

Additional advantages of my display unit arise from the compactness of construction whereby when the unit is not in use and the attendant desires to close up shop, a minimum amount of space is required to house the unit and a simple closure member provided for locking up the unit.

In closing up my new unit the rack 14 is swung further out to release the hold of the bracket 26 upon the bar 27 and the bracket 26 disengaged from the bar 27 so that the rack is free to swing by gravity into a hanging condition within the recess 12 as indicated in dotted lines. A handle 36 is provided in the apron or rail 24 so that the rack may be gently lowered into the hanging position aforesaid and also to facilitate swinging the rack 14 into extended position.

After the illuminating means 35 is extinguished in a well known manner, the lamp structure 29 is released by swinging the reflector 30 slightly clockwise (Fig. 2) to release the lug 34 from the extended end of the prop 32 and the latter being swung upward (clockwise) and the lamp structure 29 is lowered (counterclockwise) into the position shown in dotted lines Fig. 2.

It is particularly pointed out that when the rack 14 and lamp 29 are folded in, the entire unit is confined within the recess 12 inside of the opening 19. Closure means for the opening 19 is provided in the form of a roll screen unit 37 now to be explained.

Mounted upon the bottom wall 38 of the recess 12 is the roll screen unit 37 comprising a housing 39 (Figs. 11 and 12) having open ends normally closed by end plates 40 and 41. Within this housing is disposed a spring tensioned roller 42 in the form of a tube 43 mounted upon a shaft 44 extending between the end walls 40 and 41. The tube 43 is arranged concentrically on the shaft 44 by means of bearings 45 (Figs. 9 and 12) to provide freedom of movement for a coil spring 46 having one end 47 thereof extended into and fixed to the shaft 44 and its opposite end 48 bent back in a plane parallel to the shaft 44 to provide an anchor. The anchor end 48 of the spring 46 extends into an opening 49 formed in the tube 43 and normally rests in a depressed seat formation 50 thus connecting the spring 46 to the tube 43.

The spring 46 is pre-tensioned by rotating the shaft 44 prior to the final assembly. This is accomplished by allowing one end 44' of the shaft to extend beyond the end plate 40 while the opposite end just has sufficient bearing to support the shaft concentrically within the housing 39. The end 44' of the shaft 44 is provided with a drilled opening O adapted to receive a pin P and when the end 44' is extended as aforesaid a tool is connected to the opening O to wind up the coil spring 46. When a sufficient number of turns are made the pin P is placed in the opening O and the shaft 44 slid to the right (Fig. 12) until the pin P seats in a transverse groove G formed in the end plate 40. The opposite end of the shaft 44 is threaded and a nut placed thereon is drawn tight to hold the end plates 40 and 41 on the housing 39 and to anchor the shaft in fixed condition, leaving the tube 43 free to rotate.

Wound about the tube 43 is a flexible shutter member 51 in the form of a wire mesh screen having a tough plastic substance applied thereto by dipping, to form webs of such plastic substance in the normally open mesh screen and seal the entire screen off as a solid opaque panel. One end of the shutter 51 is attached to the roller 42 while the opposite or free end extends out through an opening 52 formed in the housing 39.

Mounted upon the jamb sections of the opening 19 are guide strips 53 providing inwardly exposed grooves 54 adapted to provide a track wherein the side edges of the shutter 51 may be moved vertically. The free end of the shutter 51 is provided with a bead or seam 65 to which is attached by means of bolt 55 the bar 27 heretofore referred to. A barrel type lock 56 is arranged in the central portion of the bar 27 with the keyhole of the barrel exposed to the front of the cabinet 11. A rocker arm 57 is keyed to the rotatable portion of the barrel and has pivotal connection as at 58 with a pair of latch bars 59 extending respectively to the respective sides of the bar 27. The end portions 60 of the latch bars 59 are guided for lateral movement through openings 61 formed in end walls 62 of the bar 27.

The upper end of the guide strips 53 has formed therein a keeper slot 63 into which the end portions 60 of the latch bars 59 extend when the barrel lock 56 is positioned by a key in locked condition. The end portions 60 function as latch bolts engaging in the keeper slots 63 to prevent the lowering of the bar 27.

The foregoing description makes apparent a novel arrangement of parts whereby to provide a compact and inexpensive display stand which

utilizes a minimum amount of space and yet presents a useful merchandise containing rack which may be readily installed in numerous places as well as in portions of already constructed cabinets.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A display device comprising a cabinet provided with an open front and a back wall, a shelf assembly normally occupying the interior of the cabinet and adapted to be displayed through the open front thereof and comprising a plurality of shelves positioned between a back and side walls of the shelf assembly, means providing a hinge connection between the back wall of the cabinet and the back wall of the shelf assembly to permit the shelf assembly to be pivoted from its position within the interior of the cabinet to a display position with respect thereto, a member hingedly connected to the bottom of said shelf assembly and having an intermediate portion adapted to engage the cabinet for supporting the shelf assembly in said display position, means providing the hinge connection be-

tween said member and said shelf assembly, and a flexible element connecting said member to the cabinet to limit outward pivotal movement of the shelf assembly with respect to the cabinet.

5. 2. A display case comprising a cabinet provided with side and back walls and an open front, a shelf assembly normally occupying the interior of the cabinet and adapted to be displayed through the open front thereof and comprising a plurality of shelves positioned between a back and side walls of the shelf assembly, means providing a hinge connection between the back wall of the cabinet and the back wall of the shelf assembly to permit the shelf assembly to be pivoted from its position within the interior of the cabinet to a display position with respect thereto, movable means including a bar element extending transversely of the open front, for closing the open front of said cabinet when said shelf assembly is confined in the interior thereof, lock means carried by said bar element and cooperating with an element of said cabinet to lock said movable means in closing position with respect to said open front, a member hingedly connected to the bottom of said shelf assembly and having an intermediate depending portion adapted to engage said bar element of said movable means, for supporting said shelf assembly in display position, when the movable means is disposed from closing position with respect to the open front, and means providing the hinge connection between said member and said shelf assembly.

CHARLES L. O'REILLY.
